UNITED STATES PATENT OFFICE.

MAXIMILIAN F. BONZANO, OF PHILADELPHIA, PENNSYLVANIA.

DEVICE FOR ARRESTING LOCOMOTIVES OR CARS.

SPECIFICATION forming part of Letters Patent No. 306,574, dated October 14, 1884.

Application filed May 24, 1884. (No model.)

To all whom it may concern:

Be it known that I, MAXIMILIAN F. BONZANO, a citizen of the United States, residing in Philadelphia, Pennsylvania, have invented 5
certain Improvements in Devices for Arresting Locomotives or Cars, of which the following is a specification.

My invention consists of an improvement, 10
fully described and claimed hereinafter, in the
device for arresting locomotives and cars for
which Letters Patent No. 293,846 were granted
to me February 19, 1884.

In the accompanying drawings, Figure 1 is 15
a sectional elevation of the device for which
the aforesaid Letters Patent were granted to
me February 19, 1884; Fig. 2, a sectional elevation
of the device with my improvement; Fig. 3, an end view of Fig. 2, looking in the
direction of the arrow 1; and Fig. 4, a vertical 20
section on the line 1 2, Fig. 2.

Referring, in the first instance, to Fig. 1, 25
which, as before remarked, illustrates my patented
invention, A is one of the rails of a track, and B a shoe, which has on the under
side a groove adapted to the rail, so that while
the shoe is at liberty to be moved freely on
the rail it can have no other movement independently of the said rail. To lugs on the
shoe is pivoted a lever, D, one arm, d, of which
30 extends upward, the other arm, e, of the lever
being above a block, i, resting on the rail and
being arranged to slide thereon with the shoe.
When the wheel or any other part of a locomotive or car strikes the arm d of the lever D,
35 the latter, together with the shoe and block i,
will yield and slide along the rail; but at the
same time such pressure will be exerted on
the rail, through the medium of the block, as
will cause friction enough to absorb the 40
momentum of the locomotive or car.

The object of my present invention is to so 45
restrict this friction that it cannot be in excess
of that required for the gradual stoppage of
the locomotive or car, and this object I prefer
to carry into effect by the devices illustrated
in Figs. 2, 3, 4. There is the same shoe, B,
adapted to the rail A as in my former patent,
and there are lugs b b on the shoe, to which the
lever D' is pivoted. The arm e' of the lever,

however, instead of being arranged to bear 50
directly on the block, is arranged to bear on a
spring, W, interposed between the arm and
the block.

In connection with the spring and lever 55
there must be a device for restricting the
downward movement of the arm e' and the
compression of the spring, and different
appliances for this purpose will readily suggest
themselves to skilled mechanics. In the present 60
instance the arresting device consists of a
substantial screw, Y, passing freely through
an extension of the arm e' of the lever, and
secured thereto by nuts t t. If, when a locomotive or car comes into contact with the arm 65
d of the lever D', the shock is a comparatively
slight one, the spring may be sufficient to resist
that shock before the lever is arrested by
the contact of the screw Y with the shoe B,
and the friction of the block on the rail, tending 70
to retard the movement of the shoe, and, finally,
to arrest the locomotive or car, will be proportionate to the force exerted on the arm
d of the lever. Should the shock be a violent
one, however, the spring will be compressed
only so far as the screw will permit, and hence 75
the friction will be restricted by the screw,
and cannot, if a proper spring is used, be so
excessive as to arrest the locomotive or car
too abruptly. It will be understood that the
spring must be such, as regards its rigidity and 80
resiliency, that it will be the medium, under
all circumstances, through which a proper
friction of the block against the rail will be
assured.

I claim as my invention—

The combination of a shoe, B, adapted to a 85
rail, a lever, D', pivoted to the shoe, a spring
interposed between an arm on the lever and
a block on the rail, and a device for restricting
the movement of the lever, all substantially 90
as set forth.

In testimony whereof I have signed my name
to this specification in the presence of two sub- 95
scribing witnesses.

MAXIMILIAN F. BONZANO.
